(57) **CLAIM**

The ornamental design for a ratchet tool, as shown and described.

DESCRIPTION

FIG. 1 is a front perspective view of a ratchet tool according to the invention.

FIG. 2 is a front view of the ratchet tool of FIG. 1.

FIG. 3 is a rear view of the ratchet tool of FIG. 1.

FIG. 4 is a right side view of the ratchet tool of FIG. 1.

FIG. 5 is a left side view of the ratchet tool of FIG. 1.

FIG. 6 is a top plan view of the ratchet tool of FIG. 1.

FIG. 7 is a bottom plan view of the ratchet tool of FIG. 1; and,

FIG. 8 is a rear perspective view of the ratchet tool of FIG. 1.

1 Claim, 7 Drawing Sheets(56)
